(57) **CLAIM**

I claim the ornamental design for an abrading machine, as shown and described.

DESCRIPTION

FIG. 1 is a top perspective view of an abrading machine of the present invention;

FIG. 2 is a front view thereof;

FIG. 3 is a rear view thereof;

FIG. 4 is a top view thereof;

FIG. 5 is a bottom view thereof;

FIG. 6 is a first side view thereof; and,

FIG. 7 is a second side view thereof.
